United States Patent

Des. 241,697

Patented Oct. 5, 1976

241,697

FURNITURE PANEL

Robert L. Hood, 6727 NW. 16th Terrace,
Fort Lauderdale, Fla. 33309

Filed June 6, 1975, Ser. No. 584,486

Term of patent 14 years

Int. Cl. D6—06

U.S. Cl. D6—192

FIG. 4

FIG. 2

FIG. 3

FIG. 1

FIG. 5

FIG. 6

FIG. 1 is a front elevational view of a furniture panel showing my new design;

FIG. 2 is an elevational view of the right side of the panel;

FIG. 3 is an elevational view of the left side of the panel;

FIG. 4 is a top plan view of the panel;

FIG. 5 is a bottom plan view of the panel; and

FIG. 6 is a fragmentary sectional view taken along line 6—6 of FIG. 1.

I claim:

The ornamental design for a furniture panel, as shown and described.
